UNITED STATES PATENT OFFICE.

SAMUEL W. RUSHMORE, OF PLAINFIELD, NEW JERSEY.

STARTER.

1,387,559.

Specification of Letters Patent. Patented Aug. 16, 1921.

Application filed December 20, 1920. Serial No. 431,852.

To all whom it may concern:

Be it known that I, SAMUEL W. RUSHMORE, a citizen of the United States, and resident of Plainfield, in the county of Union and State of New Jersey, have invented certain new and useful Improvements in Starters, of which the following is a specification.

My present invention is disclosed as embodied in a starter of the same type as the electric starters now commonly employed on automobiles, and while this is the preferred embodiment, it will be evident that several novel features of the device may be employed in other connections or for other purposes.

Starters of the type referred to usually comprise a small electric motor having a pinion on the armature shaft and means for moving the pinion endwise into engagement with gear teeth cut on the periphery of the fly wheel of the engine. In the type of starter now under consideration this pinion is driven through a torque spring.

My present invention relates more particularly to the torque spring in its relation to the other elements of the combination in connection with which it performs its driving and shock-absorbing functions.

According to present practice, such springs usually have their convolutions formed from material of uniform cross-section. Hence the cross section actually selected is a compromise between the great

stiffness which would be desirable to withstand unusual shocks and the flexibility which is desirable for purposes of yield under stress, particularly the stresses which are applied when the pinion teeth happen to strike end-on, instead of sliding smoothly into mesh with the teeth of the gear which is to be driven thereby. In practice this attempt to compromise conflicting requirements sometimes results in a spring stiffer

than it should be for purposes of engaging the gear and taking up the shock of starting; and even more often, it results in a spring which is so flexible that under not unusual conditions of high resistance in the engine or high speed of the starting motor, the spring may become completely wound up so that it no longer affords the desired spring resilience. This results in dangerous shock or stress on all operating

parts of the device and frequently results in 55 breakage of the spring itself.

By my invention I provide a torque and shock-absorbing spring which may be as flexible as desired under the initial torque while the pinion is meshing with the gear, 60 yet, after it is in mesh, will become as stiff as desired under maximum torque operating against maximum load. Although this may be worked out in a variety of ways, the preferred way is to make one part of the spring 65 flexible and the other part stiff, and to arrange matters so that as soon as the load becomes appreciable the flexible part of the spring will wind up and go out of business, leaving the stiffer parts in full normal 70 resiliency operation. Preferably the stiff and flexible portions of the spring merge gradually one into the other, and preferably the stiff portion of the spring is at one end, while the more flexible portion is at the 75 other end and preferably also the graduation from end to end is approximately uniform.

The preferred way to accomplish this is making the convolutions of the spring taper 80 uniformly from one end to the other. Preferably the spring is helical and preferably the convolutions are all of the same internal diameter. Preferably, the tapering is by thinning down the sides that lie adjacent 85 each other in the completed spring, and in such case the external diameter of the spring will be uniform, as well as the internal diameter.

In order to cause the flexible portions of 90 the spring to cease functioning as ordinary springs, progressively, as the torque load increases, the arrangement should be such that the free portions of the spring can become wound up so as to transmit the torque 95 mainly by longitudinal tension of the material of the spring, thus progressively shifting the spring function to progressively stiffer portions of the spring. There are various ways of accomplishing this, as for 100 instance, by providing a bearing surface against which the more flexible portions of the spring can wind themselves until further spring yield is thereby prevented. While such surface might be provided on 105 the shaft or sleeve which the spring encircles, I prefer to have surfaces of adjacent convolutions of the spring itself serve this

function. To this end the adjacent surfaces of the spring convolutions are preferably substantially flat, and they are wide enough to afford safe bearing surfaces one against the other. With this arrangement the flexible portions perform their normal spring function until the torque stress becomes sufficient to bring adjacent surfaces of the convolutions in contact. This requires that the material of the spring be stiff in a radial direction; that the initial space between convolutions be not too great; and that the organization of parts be such as will permit an endwise shortening of the spring helix as a whole.

The above and other features of my invention may be more fully understood from the following description in connection with the accompanying drawings in which:—

20 Figure 1 is a side elevation partly in axial section showing the motor, shaft, pinion and torque mechanism in operative relation to a portion of the fly wheel of an engine;

25 Fig. 2 is a diagram showing in a general way some of the characteristics of the ordinary torque spring as contrasted with those of a spring made in accordance with my invention.

In the drawings the drive shaft 1 carries 30 end-wise movable sleeve 2 having threaded thereon the toothed pinion 3. Torque is applied to pinion 3 from shaft 1 through the radial bolt 4 around which is coiled one end of spring 5, clamped by nut 6. The other 35 end of spring 5 surrounds a hollow stud 6 on sleeve 2 and is clamped in place by screw 7. The axis of shaft 1 is parallel with the axis of the fly wheel 12 and the teeth 8 of pinion 3 are in proper relation for end-wise sliding engagement with teeth 9 on said fly wheel.

The pinion 3 has the usual eccentric weight 10, the inertia and eccentricity of which are relied upon to multiply the tendency of the pinion to stand still when the driving shaft 1 is suddenly started, and also the tendency of said pinion to overrun when the shaft 1 suddenly stops or slows down, or the fly wheel 12 speeds up. On starting, 50 the quick-starting shaft and sleeve automatically screw the slow-starting pinion toward engagement with gear 9 and on stopping or overrunning, the pinion is screwed out of engagement.

55 The spring 5 normally operates to hold sleeve 2 in the position shown in the drawings, in addition to transmitting thereto the torque applied through shaft 1 and bolt 4. Sleeve 2, however, is free to yield longitudinally in a direction to compress spring 5 under various conditions, as for instance, when the teeth of pinion 8 happen to butt against the ends of teeth 9, in such case the pinion not being able to screw further to 60 the left, naturally screws the sleeve to the

right, thus endwise compressing spring 5. Conversely if the twist on spring 5 becomes very great its convolutions tend to close, thereby shortening the spring and drawing sleeve 2 to the right.

70 By reference to the drawings it will be seen that the successive convolutions 5, 5^a, 5^b, 5^c, 5^d etc. are progressively of less cross section; also that this is accomplished in the preferred way, that is, by thinning the material lengthwise of the helix, leaving the external and interior diameters of the convolutions uniform throughout the entire length of the coil; also that the adjacent faces of the convolutions are flat and substantially radial; also that they are fairly close together.

75 With the above structure for the spring, it is obvious that the initial flexibility will be that of the thinnest convolution, 5^d; also 80 that when the load gets too great for 5^d, the latter will become a mere tension member. As before stated, this may be accomplished by the winding down of the convolution to smaller diameter until it contacts 85 with sleeve 2, but preferably the proportion and arrangement of parts is such that the well known tendency of a helical spring to shorten will be availed of to bring the face of 5^d into contact with 5^e, whereupon 90 the spring will have an effective resilience equal to that of convolution 5^d; and so on progressively.

95 The proportions, particularly the degree and rate of taper of the material shown in 100 the drawings, is for purposes of illustration only, and it will be understood that this can be varied within wide limits. Preferably, however, convolution 5 is heavy enough to function normally as a helical spring, under 105 any possible strain that can occur in practice, while convolution 5^d is flexible enough for easy cushioning of concussion, either on meshing or unmeshing of pinion 3 with fly wheel 12. It is to be noted that as shown in 110 the drawings, the gap between the right hand end of the sleeve 2 and the left hand end of sleeve 11 is as great as the aggregate of all the spaces normally separating convolutions 5, 5^a, 5^b, etc. While this may be 115 desirable as permitting complete wind-up of all convolutions, it is not necessary, and in certain cases it will be found desirable to decrease this gap to afford a rear stop for the sleeve before all the convolutions have 120 come into lateral contact.

With the spring shown, it may be desirable to provide a collar 13 on sleeve 2 at the flexible end of the spring 5, to serve as an abutment plate or spool-head against which 125 convolution 5^b may flatten when the helix begins to shorten under the strain.

130 The general nature of the advantages to be derived from the above described torque spring, as compared with the prior starter

5 springs of uniform cross section are indicated diagrammatically in Fig. 2, in which the horizontal line $a-b$ is an ordinate, representing increasing angles of torque as the 10 spring is wound up under increasing load, while the vertical line $a-c$ is the ordinate indicating the increase of spring resistance according to increase of wind-up of the spring.

10 15 With reference to these ordinates the common, uniform-section, helical spring of the prior art may be considered as having resistance characteristics of the type represented by the line d, e, f , while springs constructed in accordance with my invention have characteristics like those indicated by the curve g, h, i . These curves are not supposed to be quantitatively accurate, and it is obvious that extremely wide variations, are available 20 through selection of different materials, dimensions and designs for the respective types of springs. In all cases, however, the same general characteristics will appear.

In the case of my spring the initial resili- 25 ence afforded by the spring when the torque first comes on, as represented by the vertical line a, g , may be relatively small. The increase of spring resistances, as the spring winds up will at first be very gradual, but 30 the increasing stiffness of the spring as the wind-up increases, is very marked. Moreover, when a point, as say h , has been reached there may still be a reserve of stiffness in the last turn or two of the coil that 35 will afford a substantial margin for spring yield even under extreme conditions of stress.

On the other hand, the spring of uniform 40 cross section throughout affords a more nearly proportional increase of stiffness from the start as d , to a point as e , where all the convolutions become wound up simultaneously, and further yield is practically impossible up to the breaking point of the 45 spring, as is indicated by the substantially vertical direction of the line from e to f .

A further important feature is that a uniform spring, in order to have approximately 50 the same spring resistance at e which my spring has at h , had to be made of much greater initial stiffness as indicated by vertical $a-d$ as contrasted with the initial stiffness indicated for my spring by the shorter vertical $a-g$.

55 It will be understood that these values and rates of change of values are arbitrarily selected for purposes of illustrating in a very general way the characteristic differences of the springs, and, in particular the 60 very practical fact that I can have my spring resistances at starting much lower and my maximum resistances much higher, than is possible with a spring in which the material is of uniform cross section.

65 While I have shown and described an

illustrative embodiment of my invention, it will be obvious that the coöperating driving and driven elements are capable of wide variation. Also that the torque spring between them may have its flexible portion and 70 stiffer portions associated in various ways, and arrived at by widely varying selection of materials, shapes and sizes. As for instance, the cross sectional shape of the material of the spring may be the same throughout, cross section area only being varied; or where one dimension is maintained, the maintained dimension may be longitudinally of the coil, while the diminishing dimension is radial of the coil; also, that in general the 75 great variation of cross section indicated in the drawings will usually be unnecessary since the stiffness of a spring tends to decrease in a much higher ratio than the decrease of its cross section. In this connec- 80 tion it is to be noted that where, for any reason, it is found desirable to have the great variation indicated in the drawing, as say 4 to 1, it may be desirable to regulate the taper in such a way as to give approximately 85 regular proportional degrees of spring strength, instead of merely decreasing the taper uniformly and allowing the strength to decrease, according to its own law which might be more nearly as a square or cube of 90 cross section than as a direct proportion. I have found, however, that where the taper from stiff to flexible involved decrease of cross section not greater than say 2 to 1, the taper may be perfectly uniform, with very 95 100 satisfactory results.

I claim:—

1. A starting device comprising a driving element, a rotatable element driven thereby, a power receiving and transmitting device 105 mounted to travel longitudinally on said rotatable element, and a yielding driving connection between said elements, comprising a spring having a stiff portion and a more flexible portion for the purpose described. 110

2. A starting device comprising a rotatable driving element, a rotatable element driven thereby, and an intermediate power-transmitting torque spring of the helical type, stiffer at one end and more flexible at 115 the other end than is required for normal functioning as a spring under conditions of ordinary use.

3. A starting device comprising a rotatable driving element, a rotatable element 120 driven thereby, and an intermediate power-transmitting torque spring having the material of one portion substantially thicker than another portion.

4. A starting device comprising a rotatable driving element, a rotatable element 125 driven thereby, and an intermediate power-transmitting torque spring of the helical type having convolutions in one portion of its length, flexible so as to afford relatively 130

small initial resilience at starting, and in another portion of the length substantially stiffer to withstand the strains at times of maximum driving torque and load.

5. A starting device comprising a rotatable driving element, a rotatable element driven thereby, and an intermediate power-transmitting torque spring of the helical type, stiffer at one end and more flexible at 10 the other end than is required for normal functioning as a spring under conditions of ordinary use; said driving and driven elements being relatively movable in opposition to said spring, both circumferentially 15 and longitudinally, whereby said spring may shorten under torque or thrust.

6. A starting device comprising a rotatable driving element, a rotatable element driven thereby, and an intermediate power-transmitting torque spring; said driving and 20 driven elements being relatively movable in opposition to said spring, both circumferentially and longitudinally, whereby said spring may shorten under torque or thrust; 25 and said spring being of the helical type and substantially stiffer at some points than at others, and having adjacent sides of convolutions formed to afford bearing surfaces when the length of the spring is shortened 30 with the accompanying relative longitudinal movement of said driving and driven members.

7. A starting device comprising a rotatable driving element, a rotatable element 35 driven thereby, and an intermediate power-transmitting torque spring; said driving and driven elements being relatively movable in opposition to said spring, both circumferentially and longitudinally, whereby said 40 spring may shorten under torque or thrust,

and said spring being of the helical type, substantially more flexible at one end than at the other; the parts being proportioned and arranged so that under normal full load a more flexible portion of the spring will 45 become wound up and operate as a tension member to transmit while the stiffer end continues to function as a helical spring.

8. A starter for engines comprising in combination with a motor driven shaft, a 50 screw-threaded sleeve mounted for rotary and longitudinal movement thereon, a yielding driving connection between the shaft and sleeve comprising a coiled spring which has one end anchored to the shaft and the 55 other to the sleeve, and a driving pinion which is screw-threaded upon said sleeve and adapted to travel longitudinally thereon when the shaft and its sleeve are rotated, said spring being more flexible at one end 60 than at the other for the purpose described.

9. A starter for engines comprising in combination with a motor driven shaft, a 65 screw-threaded sleeve mounted for rotary and longitudinal movement thereon, a yielding driving connection between the shaft and sleeve comprising a coiled spring which has one end anchored to the shaft and the other to the sleeve, and a driving pinion which is screw-threaded upon said sleeve and adapted 70 to travel longitudinally thereon when the shaft and its sleeve are rotated, said spring being more flexible at the sleeve end than at the shaft end and said sleeve being extended rearwardly beneath the said flexible portion. 75

Signed at New York, in the county of New York, and State of New York this 17th day of December, A. D. 1920.

SAMUEL W. RUSHMORE.
